UNITED STATES PATENT OFFICE.

DAVID MISELL, OF NEW YORK, N. Y.

ELECTRIC CIGAR-LIGHTER.

No. 839,306.

Specification of Letters Patent.

Patented Dec. 35, 1906.

Application filed January 22, 1906. Serial No. 297,362.

To all whom it may concern:

Be it known that I, DAVID MISELL, a British subject, residing in the city of New York, county and State of New York, have invented a certain new and useful Improvement in Electric Cigar-Lighters, of which the following is a specification.

Electric cigar-lighters operated by dry batteries have been hitherto used wherein the battery was combined with a filament supported thereby, which was made to glow on closing a circuit through the same by means of a push-button on the side of the battery-casing. The glowing filament was then caused to ignite an alcohol-torch, from which the tobacco could be lighted. The objection found to the employment of this device is that both hands must be used in order to operate it, and as the torch is carried in one hand while the cigar is held in the other this operation is not always convenient.

It is the object of the present invention to supply a form of cigar-lighter for use with electric batteries which is simple and inexpensive in construction and lends itself to convenient and certain operation by one hand alone. For this purpose I have devised a cigar-lighter of the class described which is so constructed that the act of presenting the alcohol-torch to the filament is sufficient to close the circuit and bring the filament to incandescence. On withdrawal of the torch the circuit opens automatically.

The present invention may take a number of different forms, some of which are exemplified in the accompanying drawings, wherein—

Figure 1 is a side elevation of a complete cigar lighter wherein the filament-casing is in permanent electric connection with the outer casing of the battery. Fig. 2 is a partial elevation of a modification wherein the filament-casing is connected electrically to the inner terminal of the battery. Fig. 3 is an elevation of a third modification, wherein the operation involves tipping the whole battery-casing; and Figs. 4 and 5 show a fourth modification, wherein a spring in the path of the torch closes the circuit.

In Fig. 1 there is shown a metallic battery-case 1, mounted upon a suitable case 2, which preferably also carries the alcohol-receptacle 3, which contains the usual torch 4. The casing 1 contains any well-known form of battery 5, which is preferably a dry bat-

tery, having an exterior cup-shaped electrode, usually zinc, and a central electrode 6, usually of carbon, with a metal top. The top of the casing 1 is cut away, so as to leave a central aperture 7. A spring 8 is soldered or otherwise fastened to the casing 1, so as to be in electric connection therewith, and at the end of this spring there is carried any appropriate form of igniting-tip 9—such, for instance, as is used in electric gas-lighters. These tips usually comprise a perforated shield 10, within which is placed a filament 11, one terminal of which is carried down to a central point underneath the tip, as at 12, while the other end of the filament is electrically connected to the exterior metallic casing of the tip, and therefore is in electric connection with the spring 8 and the outer casing 1. The mode of operation of this device is clear from Fig. 1. When it is desired to light the torch 4, the same is simply pressed against the side of the shield 10, as indicated in Fig. 1, and sufficient pressure is applied to slightly bend the spring 8 and bring the terminal 12 into contact with the top of the battery-terminal 6. This closes circuit through the filament, and the alcohol vapor surrounding the end of the torch is ignited. It will be seen that this mode of operation involves the use of only one hand, thus accomplishing the end hitherto pointed out as desirable.

In Fig. 2 is shown a modification of the invention, wherein the aperture 7 is occupied by insulation 13, which carries a metallic base 14, preferably threaded into the insulation. The spring 15 is carried by the base 14, and upon its outer end is supported the igniting-tip. Upon pressing against the shield 10, with the torch in a downward direction, the terminal 12 makes contact with the casing 1, and circuit is closed, as heretofore described. This figure illustrates the fact that my invention covers forms in which the pressure is applied to the shield 10 by the torch in any desired appropriate direction.

In Fig. 3 there is shown another modification of my invention, which is also capable of operation by merely pressing the torch against the side of the igniting-tip. In this case the outer shell of the tip is electrically connected to the outer casing 1—as, for instance, by spring 16. The casing is pivoted, as shown at 17, upon standards 18 at such a point that the whole casing tends by gravity to preserve the position shown in full lines.

The battery 5 is free to slide within the casing, so that when the latter is pressed down into the position shown in Fig. 3 in dotted lines the central terminal comes in contact 5 with the terminal 12 of the igniting-tip, and the circuit is closed. It is obvious that if the end of the torch be used to push the whole device down into the dotted-line position the alcohol will be lighted when the circuit is closed.

This invention is broad enough to cover any apparatus of this kind wherein the battery is movable within casing 1 when the latter is tipped and wherein the resulting 15 movement of the battery closes the circuit of the igniting-tip.

In Fig. 4 is shown a further modification, wherein the circuit is closed by means of a spring 19, carried by the casing 1 and electrically connected thereto, said spring being so placed as to be easily brought into contact with the igniting-tip to close the circuit. I prefer to use a circuit-closing spring of the form shown in Fig. 5, wherein the end is 25 formed into a loop. It is clear that by pressing the sponge of the torch against and partly through the loop 19 circuit is closed by the spring at the same time that the sponge is brought into contact with the 30 shield 10, or nearly so.

Various modifications may be made in this construction without departing from my invention, and I am not to be understood as limiting myself to the details herein shown 35 and described.

What I claim is—

1. An electric cigar-lighter comprising a battery, an igniting-tip having two electric

terminals connected within the tip by an igniting-filament, one of said terminals being 40 normally connected to one electrode of the battery and means supporting said tip so as to permit movement thereof to bring its remaining terminal into connection with the second electrode of said battery, substantially as described.

2. An electric cigar-lighter comprising a battery, a spring-supported igniting-tip having two electric terminals connected within the tip by an igniting-filament, one of 50 said terminals being normally connected with one electrode of the battery and the second terminal being placed close to a conducting part in electric connection with the other electrode of said battery, substantially as described.

3. An electric cigar-lighter comprising a metallic casing, a battery within the same, a spring-supported movable igniting-tip on said casing, an igniting-filament on said tip 60 having one end normally connected electrically with one electrode of said battery, and a free terminal on said tip electrically connected to the opposite end of said filament, substantially as described.

4. An electric cigar-lighter comprising an igniting-filament a movable perforated casing surrounding said filament and means operated by movement of said casing for closing an electric circuit through said filament, 65 substantially as described.

DAVID MISSELL.
